UNITED STATES PATENT OFFICE

NICK SCHLEICH AND CLARENCE J. ALDRIDGE, OF GREAT FALLS, MONTANA, ASSIGNEES
OF ONE-THIRD TO JACOB J. GOERGEN, OF GREAT FALLS, MONTANA

CAR COUPLING

Application filed December 27, 1926. Serial No. 157,256.

The invention relates to devices for coupling cars and contemplates means for simultaneously connecting the several pipes, such as the air line, the steam line, the signal line and the electrical conductors, thereby obviating separate and independent operation to couple or uncouple such parts.

The invention provides novel coupling means and unique releasing means, the coupling means being projected into operative position by gravitational action, thereby obviating the use of springs which is objectionable, mainly because of their susceptibility to derangement and impairment.

15 The invention furthermore relates to a peculiar arrangement of passages for the fluid medium and controlling means for such passages automatic in action for establishing communication between the several lines when 20 the cars are run together and for breaking the communication and closing the passages when the cars are uncoupled or separated.

While the drawings illustrate a preferred embodiment of the invention, it is to be understood that in adapting the means to meet specific needs and requirements, the design 25 may be varied and such other changes in the minor details of construction may be resorted to within the scope of the invention as 30 claimed, without departing from the spirit thereof.

For a full understanding of the invention and the merits thereof, reference is to be had to the following description and the drawings 35 hereto attached, in which,—

Figure 1 is a top plan view of a car coupling embodying the invention, showing the cooperating members in engagement and just prior to the coupling thereof in the final step.

40 Figure 2 is a horizontal sectional view of the coupling, illustrating the position of the parts after the members have been brought together into coupled relation.

Figure 3 is a vertical, central, longitudinal sectional view on the line 3—3 of Figure 2, looking in the direction of the arrows.

45 Figure 4 is a vertical transverse sectional view on the line 4—4 of Figure 1, looking in the direction of the arrows.

50 Figure 5 is a horizontal sectional view

showing one of the passages and the controlling means therefor, the parts being on a larger scale.

Figure 6 is a detail perspective view of one of the locks, and the operating means for 55 withdrawing the same into releasing position.

Corresponding and like parts are referred to in the following description and designated in the several views of the drawings by like reference characters.

The coupling contemplates cooperating companion members of like formation, but reversely disposed to admit of their meeting to couple adjacent cars when run together. Because of the like formation of the members, a detailed description of one will suffice 60 for a clear understanding of both.

65 Each of the coupling members comprises a head 1 and spaced complementary jaws 2 and 3. A lug 4 projecting from the rear end of the head 1 enters a recess formed in the head 5 of a draw bar 6 to which the coupling member is pivoted by means of a king-bolt 7. Emergency bolts 8 pass through slots 9 formed in the lug 4 and are mounted in the 70 top and bottom walls of the head 5. In the event of the king-bolt 7 giving way the emergency bolts 8 carry the load and prevent the separation of the coupling from the drawbar.

75 The jaw 3 has a plurality of passages 10 formed therein which extend through the outer or forward end of the jaw and each of which communicates at its inner or rear end with a transverse passage 11 to which a hose pipe 12 is coupled in any determinate way, 80 and which is connected to the proper train line for the flow of oil, steam or other fluid medium. The outer end of each of the passages 10 is enlarged and receives a packing 13 which is held in place by means of a retainer 14 which consists of a ring threaded 85 into the forward enlarged end of the packing.

A longitudinal chamber 15 is formed in the head 1 opposite the space formed between the jaws 2 and 3 and receives a piston valve 16. The transverse passage 11 is intersected by the valve chamber 15 and the piston valve 16 is formed with a transverse opening 18 and a longitudinal opening 19.

90 When the piston valve 16 occupies a position 95 100

at the limit of its rearward movement when pressed into the valve chamber 15, the opening thereof registers with the passage 11, thus establishing communication between the passages of the coupling members and between the train lines of adjacent cars. An open helical spring 20, within the rear portion of the valve chamber 15, normally urges the piston valve 16 forwardly. A projection 21 at the inner or rear end of the piston valve 16 enters an opening 22 formed in the head 1 and these parts are of noncircular outline to preserve the relative position of the piston valve to insure registering of the opening 18 with the passage 11 when the piston valve is moved rearwardly within the valve chamber 15. The forward portion of the piston valve 16 is reduced and operates through a ring 23 threaded into the outer end of the valve chamber 15 which serves as a stop to limit the forward movement of the piston valve. A tapered extension 24 at the outer end of the piston valve is adapted to enter the enlarged outer end of the passage 10, a tight joint being assured by means of the packing 13 and ring 14. It is to be understood that a piston valve is provided for each of the passages 10 and that a passage is had for each train line. As indicated most clearly in Figures 3 and 4, three passages 10 are provided, one for the air line for the brake system, one for the steam line for heating, and one for the signal line. In addition to the three passages 10, there is provided a similar passage for the reception of an electric conductor 25, said passage having its forward end enlarged to receive a socket 26, which is electrically insulated from the coupling member. A chamber 27 is formed in the head 1 opposite the space separating the jaws 2 and 3 and receives a circuit closer which is pressed forwardly by open coil springs 28 and 29. A ring 23a fitted in the outer end of the chamber 27 limits the forward movement of the circuit closer. The circuit closer comprises sections 30 and 31, the spring 28 being disposed between said sections and the spring 29 being arranged between the rear wall of the chamber 27 and the section 31, whereby to press the latter forwardly and break the connection between it and a socket 32, to which a flexible conductor 33 is connected. When the members are uncoupled the circuit closer is pressed forwardly by means of the spring 29, thereby breaking the connection between it and the socket 32. When the members are coupled the circuit closer is pressed rearwardly and engages the socket 32, thereby establishing a connection between the conductors 25 and 33, it being remembered that the projecting end of the section 30 enters and makes electric connection with the socket 26.

The jaw 2 has a recess 34 formed therein and a lock 35 is pivotally mounted within

the recess 34 and has its rear end normally projecting beyond the inner side of the jaw 2, so as to enter a recess formed in the outer side of the jaw 3 of the companion member. The lock 35 consists of a block and is pivoted at its forward end within the recess 34. The lower face of the lock 35 is inclined laterally and rests upon the bottom of the recess 34 which is laterally inclined, as indicated at 37. The lateral inclination of the contiguous faces 36 and 37 is such as to effect a lateral movement of the block and hold its rear end projecting beyond the inner side of the jaw 2, so as to engage the forward wall of the recess 38 formed in the outer side of the jaw 3 of the companion member. The rear end of the lock 35 is provided with a projection 39 which is adapted to ride upon an inclined portion 40 of an operating member having a stem 41, which projects beyond the member to be operated from above or below as required. Upward movement of the stem 41 causes the incline 40 to ride upon the projections 39 and move the rear end of the lock 35 within the recess 34, thereby withdrawing its rear end from engagement with the jaw 3 so that the members of the coupling may be separated. A lock release 42 is pivoted at one end within the recess 38 and its rear end is adapted to be moved laterally to effect disengagement of the adjacent lock 35 from the forward wall of the recess 38. An operating member 43, similar to the lock operating member 41, is mounted in a vertical opening formed in the jaw 3 and in communication with the recess 38. The operating member 43 has an inclined portion 44 to effect lateral movement of the lock release 42. The stem of the member 43 projects beyond the coupling member to be operated from above or below. As shown, the stems of the members 41 and 43 project above the top of the coupling member and are connected to arms 45 and 46 projecting from the shaft 47, which may be operated from either side of the car. As the member 43 is moved upwardly the inclined portion 44 rides upon the lock release 42 and moves it laterally to press the adjacent lock 35 within the recess 34, while at the same time, the opposite lock 35 is withdrawn within its recess by the inclined portion 40 riding upon the projection 39. It is observed that rotation of the shaft 47 effects simultaneous upward movement of both members 41 and 43 connected to the arms thereof, the member 41 withdrawing the lock 35 of the coupling member upon which the shaft is mounted and the member 43 projecting the lock release so as to disengage the lock 35 of the companion jaw from the jaw containing the positively operated lock release 42. The upper ends of the recesses 38 and 40 are closed by cup plates, as indicated most clearly in Figures 1 and 4. The jaws 3 of the coupling members are adapted to

enter the spaces formed between companion jaws. The recesses 38 are formed in the outer side of the jaws 3, whereas the recesses 34 are formed in the inner side of the jaws 2. In consequence of this arrangement, the locks 35 carried by the jaws 2 engage the forward ends of the recesses formed in the jaws 3 and when uncoupling the cars one of the locks 35 is directly released by the member 41, and the other lock is released by the member 42. It will thus be understood that there is a positive lock between corresponding jaws 2 and 3 of the coupling members, both locks being simultaneously released by operation of either one of the shafts 47, or other means provided for actuating the members 41 and 43. When the cars to be coupled are run together the several train lines and electric conductors are simultaneously coupled, thereby establishing communication between the respective train lines and electric conductors. When the cars are uncoupled the several train lines are automatically closed to prevent any waste of the air or steam, and the circuit closing device for connecting the electric conductors assumes a neutral position, so that the projecting portion may not have any current taken therefrom by contact of an object therewith.

30 The conductor 25 is electrically connected with the socket 26, and the conductor 33 is electrically connected with the socket 32. Hence, the conductors 33 and 25 are electrically connected when the cars are coupled.

35 Having thus described the invention, we claim:

1. A car coupling comprising a member having spaced jaws and having a recess formed in one of the jaws and opening 40 through a side thereof, the bottom of the recess being laterally inclined, a lock pivoted within the said recess and having its bottom side laterally inclined to coact with the laterally inclined bottom of the recess to normally hold the lock projected into operative position, and means for moving the lock into inoperative position to admit of uncoupling.

2. A car coupling comprising a member including a head and spaced jaws projecting 50 therefrom, one of the jaws having a longitudinal passage opening through the extremity thereof, and the head having a transverse passage in communication with the inner end of the said longitudinal passage, and having a 55 valve chamber intersecting the transverse passage and opening into the space formed between the jaws, and a spring actuated valve in said chamber normally projecting into the space formed between the jaws and interrupting the transverse passage and adapted to be pressed inward to admit of uninterrupted flow through the passage when the cars are coupled.

3. A car coupling comprising a member 60 including a head and spaced jaws projecting

therefrom, one of the jaws having a longitudinal passage opening through the extremity thereof, and the head having a transverse passage in communication with the inner end of the said longitudinal passage, and having 70 a valve chamber intersecting the transverse passage and opening into the space formed between the jaws, and a spring actuated valve in said chamber normally extending into the space provided between the jaws and formed with intersecting transverse and longitudinal openings, the transverse opening being normally out of line with the said transverse passage and adapted to register therewith when the valve is pressed in by a coupling of 75 80 the cars.

4. A car coupling comprising a member including transversely spaced portions defining jaws, one of the jaws having a recess extending through its inner face, and having the 85 bottom of the recess transversely inclined inwardly and downwardly, a lock pivoted in a recess and having its bottom side laterally inclined to coact with the inclined bottom of the recess to normally hold the lock projected, 90 and lock releasing means mounted in the recess jaw.

In testimony whereof we affix our signatures.
